CLAIM

The ornamental design for a display screen with a graphical user interface, as shown and described.

DESCRIPTION

FIG. 1 is a first embodiment of a display screen with a graphical user interface.

FIG. 2 is a second embodiment of a display screen with a graphical user interface.

FIG. 3 is a third embodiment of a display screen with a graphical user interface.

FIG. 4 is a fourth embodiment of a display screen with a graphical user interface.

FIG. 5 is a fifth embodiment of a display screen with a graphical user interface.

FIG. 6 is a sixth embodiment of a display screen with a graphical user interface.

FIG. 7 is a seventh embodiment of a display screen with a graphical user interface.

FIG. 8 is an eighth embodiment of a display screen with a graphical user interface; and,

FIG. 9 is a ninth embodiment of a display screen with a graphical user interface.

The broken lines in the drawings depict the display screen and associated graphics of the graphical user interface and form no part of the claimed design.

1 Claim, 9 Drawing Sheets
